UNITED STATES PATENT OFFICE.

WILLIAM H. EDDY, OF WORCESTER, MASSACHUSETTS.

MACHINE FOR TAPPING NUTS.

SPECIFICATION forming part of Letters Patent No. 388,851, dated September 4, 1888.

Application filed June 15, 1885. Serial No. 168,702. (No model.)

To all whom it may concern:

Be it known that I, WILLIAM H. EDDY, a citizen of the United States, residing at Worcester, in the county of Worcester and State 5 of Massachusetts, have invented certain new and useful Improvements in Machines for Tapping Nuts, of which the following is a specification containing a full, clear, and exact description of the same, accompanied by drawings representing a nut-tapping machine embodying my invention, in which—

Figure 1 is a front elevation; Fig. 2, a vertical sectional view; Fig. 3, a perspective view showing the mouth of one of the separators. 15 Fig. 4 is an end view of the sliding nut-holder, as shown in Fig. 5. Fig. 5 is a detached and top view of the sliding nut-holder. Fig. 6 is a top view of the hopper and separators. Fig. 7 is a horizontal sectional view of the machine. 20 Fig. 8 is an end view of one of the rotating tap-holding chucks. Fig. 9 is a sectional view of the same. Fig. 10 is a detached view of the rotating head and its locking device. Fig. 11 is a sectional view showing the arrangement 25 of the driving-shafts and actuating-cams. Fig. 12 shows the device for withdrawing the tap. Fig. 13 shows the same with the tap withdrawn. Fig. 14 is a sectional view, and Fig. 15 an end view, of the same. 30 Similar letters refer to similar parts in the several views.

My invention has for its object to automatically present the nut-blanks to the tapping mechanism, and also to automatically remove the threaded nuts from the taps. I attain these 35 objects by means of the mechanism hereinafter described, and specifically set forth in the claims.

A A represent the frame of the machine, upon 40 which are mounted the several operating parts, and within which are contained in the main the actuating mechanism.

B is the driving-shaft, to which power is applied through a belt-pulley, a, and a yielding spring-clutch, a', of any known construction, by which an undue resistance will check the operation of the machine before breakage occurs and allow the driving-pulley to run on the shaft B. 45

50 Rotary motion is imparted to the gear c on the main driving-shaft through the interme-

diate gear, c', and its attached pinion c'', both running on a stud in the frame, and the gear c' on the shaft C, and through the miter-gears d, d', and d'' to the shafts D, E and E', said 55 shafts C, D, E, and E' carrying the several actuating-cams, hereinafter mentioned.

A bevel-gear, e, on the shaft C drives through a bevel-gear, e', on a short vertical shaft journaled in a bearing attached to the frame of 60 the machine and having the arm e'', carrying at its outer end a stud or roll, e'', which at each rotation of the arm e'' enters one of a series of four radial slots, e'', Fig. 2, in a plate-wheel attached to the vertical shaft F, to which the 65 head G is attached, carrying the revolving tap-holding chucks f. At each rotation of the arm e'' the head G is turned one-quarter of a revolution, bringing the taps f' in the position shown in Fig. 7, with a period of rest 70 between each quarter-rotation of the head G to allow the operation of tapping the nuts to be performed. Upon the vertical shaft F the sleeve F' turns, having a bevel-gear, F'', driven by the bevel-gear F' on the driving-shaft B, and 75 a bevel-gear, F'', engaging beveled pinions F'', by which the tap-holding chucks f are revolved.

H H H are the nut-holders, sliding in ways attached to the frame and actuated by the bent levers H', cams H'', and weights H''. 80 Tubular stacks or chutes I are attached to the upper sides of the ways supporting the sliding nut-holders H, and to the upper ends of the stacks are hinged the separators I', with their ends resting in a rotating hopper, J, 85 driven by a belt-connection from the vertical shaft C, which is geared by the miter-gears to the shaft C. The nut-blanks are placed in a mass in the hopper J and brought by its motion against the mouths of the separators I' in 90 a manner similar to that known as the "Sloan feed" in screw-machines. In my machine, however, I form the mouths of the separators in the form shown in Fig. 3, with the upper and under sides projecting and forming triangular lips g' and g''. The pointed lips serve to part the mass of nut-blanks, which would otherwise clog the mouth, and receive those nut-blanks which are presented in a horizontal position between the lips. The separators are 95 connected by springs g' with a swinging lever, I'', which is actuated by a pin, g, on the bevel- 100

- gear g^2 , driven by a similar gear on the shaft C' , so that at stated intervals the separators are raised, allowing the nut-blanks contained in them to slide into the stacks or chutes I. The 5 lower nut-blanks in the column of nuts held in the chutes I fall into the recessed ends of the sliding holders II, when they are held in their normal position by the cams H^2 , the blanks resting on the plate b , and when the taps are 10 presented to the nut-blanks the rotation of the cams H^2 allows the weights H^3 to fall and carry the nut-holding slides II forward, as shown by broken lines in Fig. 5, the revolving taps cutting a thread in the nut-blanks and entering 15 holes h , Fig. 4, in the slides. The nut-blanks are securely held in the recessed ends of the slides II by blade springs h' , attached to the sides of the slides II and having their ends bent at right angles over the end of the slide, 20 so as to prevent the blank from falling out. These springs are held against the slides by the inclosing frame-work, which allows them to expand when the slide is carried forward and release the nut. 25 The operation of tapping the three blanks in each of the slides by the taps f' is carried on simultaneously, and each nut is carried over the threaded portion of the tap upon the plain portion or neck, so that each tap as it is 30 brought around and presented to the nut-releasing devices will have three nuts, i , Fig. 12, strung upon it. As each tap leaves the last nut-holding slide on the right of the machine, it enters a slotted plate, K, curved eccentrically to the axis of the rotating head G, so that as the tap is carried through the slot in the plate its threaded portion and the shallow groove j in the tap will be carried entirely 35 through the plate K, which will crowd the nuts back toward the chucks. 40 The nut-releasing devices consist of a plate, L, sliding in ways mounted on the bed of the machine and carrying the bent pivoted levers k , with their inner ends adapted to seize the tap at the groove j . The plate L carries in a 45 chamber the spiral spring k' , Fig. 14, with its end resting against the plate k^2 , attached to the supporting-ways, by which spring the plate L is held against the end of the slotted plate K 50 in the position shown in Fig. 12. A wedge-shaped block, k^3 , sliding in a slot, k^4 , in the plate L, is moved outward when the tap is brought between the opposing jaws of the levers k , by means of the lever L' , pivoted to 55 the frame at k^5 , Fig. 1, and actuated by a suitably-formed cam, L^2 , Fig. 11. As the wedge-shaped block k^3 is carried between the outer ends of the levers k , their jaws are brought against the grooved portion j of the tap and 60 the sliding plate L drawn back into the position shown in Fig. 13, compressing the spring k' and withdrawing the tap from the revolving chuck f and carrying it through the slotted plate K, thereby stripping off the nuts i . 65 By reversing the motion of the wedge-shaped block k^3 the tension of the spiral spring k' will carry the plate L back into the position in

Fig. 12 and return the tap to the chuck. The jaws of the levers k are arranged in a vertical plane and the taps f' are successively 70 brought between the jaws by the intermittent rotary motion of the head G, and as each tap is brought into position between the jaws its end is brought in contact with the beveled surface of the head l of the bolt l' , pushing the 75 bolt outward and compressing the spiral spring l' , whose tension, pressing against the end of the tap, insures its complete entrance into the revolving chuck. The shank j' of the tap is square, fitting a rectangular space, m^2 , 80 Fig. 8, formed by the face of the jaws M' in the revolving chucks.

The construction and operation of the revolving chucks are shown in Fig. 2, and more fully in detail in Figs. 8 and 9. They consist 85 of hollow spindles M, held in equidistant and radial bearings in the rotating head G. The larger and outer ends of the hollow spindles M carry a pair of jaws, M', fulcrumed on the screws m , against which they are held by the 90 spring m' . I countersink the ends of the jaws at m^6 , Fig. 9, to allow the ready admission of the tap to the jaws, and at the inner end of the face of the jaws I form a projecting shoulder, m^3 , to limit the entrance and receive the 95 end-thrust of the tap. The action of the spring m' is applied to the jaws slightly in front of the fulcrum-screws m , so the rear ends, m^4 , of the jaws press upon a sliding pin, M^2 , held from turning by a screw, m^5 , entering a 100 groove in the pin. The pin M^2 holds the rear ends, m^4 , of the jaws apart, so as to hold the shank j' of the tap firmly in the chuck, and the release of the tap is effected by sliding the pin M^2 and bringing the thinner section (shown at m^7 , Fig. 9) between the ends 105 m^4 , allowing the outer ends of the jaws to open slightly and permit the tap to be withdrawn. As soon as the tap is returned, a reverse sliding motion is given to the pin M^2 , 110 and the tap again seized by the jaws M'. Necks m^8 on the pins M^2 are engaged by the vertical forked levers N, Fig. 2, pivoted in lugs attached to the revolving shaft F, and as each of the revolving chucks is brought by 115 the intermittent rotation of the head G into position to present its tap to the action of the withdrawing mechanism, already described, and shown in Figs. 12 to 15, the corresponding vertical lever, N, will be brought into position to be engaged by a sliding plate, N', 120 Fig. 7, having a transverse curved groove on its underside lying in the path of the button-shaped head n of the vertical levers N, and into which they are successively brought. The 125 proper sliding motion is given to the plate N' by means of the horizontal pivoted lever N², connected to the upper end of the vertical pivoted lever N³, whose lower end is actuated by a cam, N⁴, attached to the shaft C, said cam 130 having a suitably-formed slot on its side to effect the outward sliding motion of the plate N' through the intervening mechanism, consisting of the lever N³ and plate N², at the same

time the levers k seize the tap, and to reverse its motion when the tap has been returned to the chuck. During the period of rest of the head G , while the operation of tapping by three of the taps and that of stripping the tapped nuts from the fourth tap is being carried on, I lock the head G by means of a vertically-sliding and weighted pin, P , (shown in detail in Fig. 10,) which is carried up by a cam, P' , on the shaft C and held in one of the four equidistant notches p in the under edge of the head G . In case any of the nuts fail to pass completely over the threaded portion of the tap they will be brought against the eccentrically-curved slotted guard-plate K and the machine stopped whenever the resistance exceeds the force of the motive power as applied to the machine.

As the several chucks are constantly revolving, their jaws M' should only be opened far enough to release the tap when seized by the withdrawing mechanism, so the tap when returned will be rotated as soon as its squared shank j' is brought coincident with the rectangular space in the jaws M' ; otherwise it will be liable to be seized by its corners and the sliding pin M^2 prevented from entering.

In my mechanism for feeding the nut-blanks I use a hopper of a peculiar form, having its upper edge, J' , turned inward to return any blanks which may be forced up the side to the center; and at the center of the hopper I form the cone J^2 , forming an annular valley or depression, into which the mouths of the separators are carried, so the hopper may be nearly or quite cleared of blanks. On the upper sides of the separators I place the lozenge-shaped blocks o , with their acute angles presented to a blank sliding along the upper surface of the separator, thereby returning them to the hopper.

A spring-check, o' , retains the column of blanks in the separator as it is raised until its alignment with the chute I is secured. The springs g^6 yield whenever any obstruction is offered to the swinging action of the separators.

What I claim as my invention, and desire to secure by Letters Patent, is—

1. The combination of a head having an intermittent rotary motion, a continuously-rotating gear concentric with said head, a series of chucks journaled in said head and having gears engaged by said concentric gear, taps held in said chucks, and mechanism, substantially as described, for presenting the nut-blanks to said rotating taps.

2. The combination, with a tap and connected mechanism for rotating the same, of a sliding plate sliding in ways attached to the frame of the machine for the purpose of carrying the blank against the rotating tap, and elastic blades attached to the sides of said sliding plate and held against the nut blank by their contact with the ways of the sliding plate, substantially as described.

3. The combination, with a tap having connected means for rotating the same, of a slid-

ing plate for presenting the nut-blanks to the tap, a bell-crank lever having one arm connected with said sliding plate and the opposite arm weighted, and a rotating cam by which the fall of said weighted arm is determined and the action of the lever reversed, substantially as described.

4. The combination, with a rotating hopper, of a hinged separator and a stationary receiving stack, said separator being provided at its lower end or mouth with the pointed projecting lips $g^3 g^4$, by which the nut blanks coming in contact with said lips are parted laterally, substantially as described.

5. The combination, with the separators, substantially as described, of the lozenge-shaped guards attached to the upper surface of the separators, as and for the purpose set forth.

6. The combination, with a revolving hopper for holding the nut-blanks and one or more vibrating separators, of yielding spring-connections connecting said vibrating separators with actuating mechanism for raising them at intervals, substantially as described, and for the purpose set forth.

7. In a nut-tapping machine, the rotating hopper having its sides turned inwardly at the top, in combination with a separator having a triangular pointed mouth for parting the nut-blanks laterally, substantially as described.

8. The combination, with a rotating head carrying one or more revolving taps, of a curved and slotted guard-plate placed eccentrically to the rotating head and through whose slot the taps are successively carried, as and for the purpose set forth.

9. The combination, with a rotating head carrying a series of revolving tap-holding chucks, of a series of tap-holding chucks journaled in bearings in said head and consisting of a hollow spindle carrying jaws having mechanism for opening and closing the same, said jaws forming a rectangular space to admit the shank of the tap, countersunk in front at m^2 , and having interior shoulder or projection, m^3 , to receive the end-thrust upon the tap, as and for the purpose set forth.

10. The combination of the hollow spindle M , jaws M' , fulcrumed on the adjusting-screws m , adjusting-screws m' , carried in the spindle M , spring m' , placed between said jaws and in advance of said fulcrum-screws, and a sliding pin, M^2 , having the inclined surfaces m^4 and flattened section m^5 , substantially as described.

11. The combination of a head having an intermittent rotary motion, a series of tap-holding chucks journaled in said head and having a continuous rotary motion, taps held in said chucks, a series of sliding plates for presenting the nut-blanks to said taps, and withdrawing mechanism for withdrawing said taps from their rotating chucks, all combined and operating substantially as described.

12. The combination, with a head having an intermittent rotary motion, and a series of chucks journaled in said head and having a

continuous rotary motion, of a pair of withdrawing-jaws for seizing the taps between their threaded portion and their shanks, and a slotted plate through which the taps are drawn by said withdrawing jaws and by which the nuts are stripped from the shanks of said taps, substantially as described.

13. The combination of a rotating tap holding chuck, a tap held in said chuck and having an annular groove to receive a pair of withdrawing jaws, and a pair of withdrawing-jaws pivoted upon a sliding plate having a sliding motion toward and away from said tap-holding chuck, substantially as described.

14. The bent pivoted levers k , sliding plate L , spring k' , and sliding wedge-shaped block k'' , with mechanism for actuating the same, all combined and operating as described, and for the purpose set forth.

15. The combination, with the rotating chucks f , carrying taps f' and held in a head having an intermittent rotary motion, and mechanism, substantially as described, for withdrawing said taps from and returning

20 them to their chucks, of the sliding bolt l' , having a head, l , with a beveled surface lying in the path of the taps f' as they are carried

by the rotating head, and a spring, l'' , as and for the purpose set forth.

16. The combination, with a head having an 30c intermittent rotary motion and carrying a series of tap-holding chucks journaled in said head, of a locking device consisting of a sliding pin, P , entering a hole in said head and provided with a weight and a rotating cam, 35 P' , substantially as described.

17. The combination of jaws M' , springs m' , sliding pins M'' , levers N , all carried in a head having an intermittent rotating motion, and sliding plate N' , adapted to engage and actuate 40 each of the levers N successively as they are brought beneath it, with mechanism for operating the sliding plate conjointly with the mechanism for withdrawing the tap, as and for the purpose set forth.

18. The combination, with a rotating tap, of plate b , sliding holder H , sliding in ways fixed to the frame of the machine, stack I , and elastic blades $h' h''$, attached to the sliding holder H , substantially as described.
